UNITED STATES PATENT OFFICE.

LEWIS FERRY MOODY, OF PHILADELPHIA, PENNSYLVANIA.

IMPULSE TURBINE.

Application filed May 26, 1923. Serial No. 641,688.

To all whom it may concern:

Be it known that I, LEWIS FERRY MOODY, a citizen of the United States, residing at Philadelphia, in the county of Philadelphia and State of Pennsylvania, have invented certain new and useful Improvements in Impulse Turbines, of which the following is a specification.

This invention relates to impulse turbines and particularly to impulse turbines having a jet of cylindrical form directed against buckets carried at the periphery of the runner. The object of the invention is to provide such a turbine having the jet or jets directed into the peripheral portions of the buckets and turned by the buckets and discharged on one side of the rotor.

Further objects of the invention particularly in turning and spreading the flow in gradual and efficient manner will appear from the following description taken in connection with the accompanying drawings in which

Fig. 1 is a vertical sectional view through a runner of a turbine embodying the invention.

Fig. 2 is a horizontal sectional view on line 2—2 of Fig. 1.

Fig. 3 is a sectional development of buckets of the Fig. 1 runner taken on the cylindrical surface indicated at 3—3 in Figs. 1 and 2.

Fig. 4 is a vertical sectional view of a modified form of runner.

Fig. 5 is a plan view of the same, and Figs. 6, 7 and 8 are sectional views of the runner buckets taken on cylindrical surfaces 6—6 and 7—7 and conical surface 8—8 respectively of Figs. 4 and 5.

In the specific embodiment of the invention shown in Figs. 1 to 3 a vertical shaft carries at its lower end the runner 11 having hub portion 12 carrying the peripheral buckets 13 sixteen in number. The surface 14 of the hub 12 at the buckets is concave in section curving smoothly from a radial direction at the entrance edges 15 of the buckets toward an axial direction at the discharge edges 16.

From this surface the buckets 13 extend downward and outward in shallow curved form adapted to receive and turn and spread the cylindrical jet from nozzle 17 as indicated by broken lines on the drawings. The horizontal elements of each bucket face 20

taken in horizontal planes are relatively flat concave curves (Fig. 2) from the bucket tips 18 to the line 19 of junction with the hub service 14 while the vertical elements taken in vertical cylinders coaxial with the runner are more deeply concave (Fig. 3) curving forward and then backward to the discharge edge 16. The faces 20 of the buckets as cut by a horizontal plane (Fig. 2) incline forward and outward to form an angle β_1 in their entrance portions with relation to tangents to the circle of revolution at the blade tips of the runner, to cooperate properly with the jet which is directed horizontally against the buckets with both tangential and inward components. The direction of the jet is somewhat more inward than tangential, forming a relatively large angle α_1 with the tangential direction. Such an inclination of the jet together with the forward inclination of the buckets gives a relatively high bucket velocity and high speed of rotation of the runner.

The water in passing through each runner bucket 13 is simultaneously spread and turned into a backward direction making a small angle β_2 with the tangential direction, so that its relative velocity is nearly equal and opposite to the motion of the bucket at the point of discharge; and the water is discharged from each bucket as a thin sheet and with but little absolute velocity remaining in it. The inner lines of flow 22, as to their meridian components, are curved gradually from a radial inward direction into a nearly axial direction and the outer lines 23 are curved around from radial inward to a downward and outward direction. Between these extremes the jet is spread out gradually in thin sheet form, discharging downward in a generally axial direction. Owing to the large angle α_1 between the jet and the tangential direction, that is, the direction of motion of the buckets where the water enters, the flow will have a large inward velocity component normal to the motion of the wheel. When the water leaves the buckets, on the other hand, it must have a small component of velocity perpendicular to the motion of the wheel, since otherwise there would be an undue loss of energy in the velocity head of the water leaving the runner. Considering the components of flow in a plane containing the runner axis, therefore, the component in this plane at en-

trance will be large and the component at discharge must be small. The flow is therefore spread out laterally so that the width of the flow at discharge is much greater than that of entrance in order to provide the necessary area of discharge.

In the runner of Figs. 1 to 3 the flow is turned from radial toward axial entirely by the bucket surfaces without contact with the surface 14 of the runner crown or hub 12. The extended line of connection between each bucket and the crown 12 provides a strong support for the buckets and usually a shroud ring will be unnecessary, leaving the exposed edges of the buckets free and giving easy access to the bucket surfaces for grinding and finishing.

In the modification shown in Figs. 5 to 8 the runner hub or crown 32 has its concave peripheral surface 34 provided with the buckets 33 having concave faces 30 receiving the jet from nozzle 37 at the entrance edge 35 and turning and spreading and decelerating the flow to finally discharge it at 36 as a thin sheet between the inner lines 42 and the outer lines 43. The entrance edges 35 are contained in a vertical cylindrical surface and the lower portions of the buckets are extended laterally to provide for a wide lateral spreading of the jet as it passes through the bucket.

The faces 30 of the buckets merge smoothly with the surface 34 of the runner crown and part of the guidance of the water is provided by this surface 34. The shape of the bucket is shown in Figs. 6, 7 and 8 in developed sections cut by cylindrical or conical surfaces. The jet flow is received with inward and tangential components and while it is being spread and turned backward it is guided downward and outward to a generally axial discharge. The buckets 33 instead of inclining outwardly and forwardly at their entrance portions 35 are nearly radial at these portions as viewed in horizontal section or inclining slightly backward and outward. Progressing inwardly toward the hub these buckets curve inward and backward on smooth lines which reach a substantially tangential direction at the line of emergence with the crown surface 34.

In both the runners shown successive buckets overlap in axial projection as indicated in Figs. 2, 3, 5, 6 and 7 so that the discharge edge of one bucket lies under the upper entrance portion of the following bucket. While only one nozzle is shown in the drawings it is obvious that a plurality of nozzles may be used and the turbine installed in any desired setting adapted for instance to maintain a partial vacuum in the runner chamber. The jets may be directed at any desired angle so as to vary the relative inward and tangential components to suit different conditions and without de-

parting from the principle of the invention various modifications may be resorted to within the scope of the appended claims.

In particular, the forward inclination of the buckets at the point of entrance as shown in Fig. 2 in combination with the large angle α_1 between the jet and the direction of motion of the vane edges is advantageous in securing a high velocity of the buckets and a high specific speed of the turbine, and when a very high specific speed is desired the angle α_1 can be made greater than 45° and the buckets inclined forward with a considerable angle β_1 . In securing a high specific speed, it will be advantageous in many cases to combine the forward inclination of the buckets of Fig. 2 with the lateral extension of the discharge edges of the buckets shown in Fig. 4. This may be done either by modifying the runner of Figs. 1 and 2 to extend the outflow edges of the blade outwardly from the axis to a greater diameter than the inflow edges or by modifying the runner of Figs. 4 and 5 so as to give the entrance edges of the vane a forward angle of 80° to 90° with respect to the radius similar to that shown in Fig. 2. When the laterally extended buckets are used, this outward extension may for high specific speeds be carried to the extent where the buckets will extend under and beyond the nozzle, the entrance portion of the bucket being cut away sufficiently to clear the nozzle. It is desirable to have the nozzle orifice as close as possible to the entrance edges of the buckets in order to minimize the length of free path traversed by the jet between the orifice and the bucket edges. The nozzles indicated in the figures are of the type in which the size of the jet is controlled by a central 105 needle. The needle may be of relatively short form having the sides of its tip converge at a considerable angle at the point, thus permitting the nozzle to be placed close to the vane edges.

I claim:

1. In an impulse turbine means for forming a cylindrical free jet having its axis substantially in a plane perpendicular to the runner axis, and a runner having buckets receiving said jet and turning all of it toward the axial direction and discharging it on one side of the runner, the flow between adjacent buckets having a free surface.
2. In an impulse turbine means for forming a cylindrical free jet having its axis substantially in a plane perpendicular to the runner axis, and a runner having buckets receiving said jet and turning all of it toward the axial direction and discharging it on one side of said plane, the flow between adjacent buckets having a free surface.
3. In an impulse turbine means for forming a cylindrical free jet having its axis substantially in a plane perpendicular to the

runner axis, and a runner having buckets receiving said jet and turning all of it toward the axial direction and discharging it in a generally axial direction on one side of the runner, the flow between adjacent buckets having a free surface.

4. In an impulse turbine means for forming a cylindrical free jet having its axis substantially in a plane perpendicular to the runner axis, and a runner having buckets receiving said jet and turning all of it toward the axial direction and spreading it laterally so that the inner lines of the discharge have inward components and the outer flow lines have outward components, the flow between adjacent buckets having a free surface.

5. In an impulse turbine means for forming a cylindrical free jet having its axis substantially in a plane perpendicular to the runner axis, and a runner having buckets receiving said jet and turning all of it downward toward the axial direction and discharging it downward on one side of the runner, the flow between adjacent buckets having a free surface.

6. In an impulse turbine means for forming a cylindrical free jet having its axis substantially in a plane perpendicular to the runner axis, and a runner having buckets receiving said jet and turning all of it toward the axial direction and discharging it on one side of the runner, said jet having both tangential and radial components at the point of entrance to said buckets, the flow between adjacent buckets having a free surface.

7. In an impulse turbine means for forming a cylindrical free jet having its axis substantially in a plane perpendicular to the runner axis, and a runner having buckets receiving said jet with a free surface for the flow between adjacent buckets and turning all of it toward the axial direction and spreading it laterally so that the inner lines of the discharge have inward components and the outer flow lines have outward components, said jet having both tangential and radial components at the point of entrance to said buckets.

8. In an impulse turbine means for forming a cylindrical free jet having its axis substantially in a plane perpendicular to the runner axis, and a runner having buckets with faces inclined forward and outward and turning all of said jet to one side of said plane, the flow between adjacent buckets having a free surface.

9. In an impulse turbine means for forming a cylindrical free jet having its axis substantially in a plane perpendicular to the runner axis, and a runner having buckets with faces inclined forward and outward and turning all of said jet to one side of said plane, said jet at the point of entrance to

the buckets having both radial and tangential components, and the flow between adjacent buckets having a free surface.

10. In an impulse turbine means for forming a cylindrical free jet having its axis substantially in a plane perpendicular to the runner axis, and a runner having buckets with faces inclined forward and outward and turning all of said jet to one side of said plane and discharging it in a generally axial direction, said jet at the point of entrance to the buckets having both radial and tangential components, and the flow between adjacent buckets having a free surface.

11. In an impulse turbine means for forming a cylindrical free jet having its axis substantially in a plane perpendicular to the runner axis, and a runner having buckets with faces inclined forward and outward and turning all of said jet to one side of said plane and discharging it downward in a generally axial direction, said jet at the point of entrance to the buckets having both radial and tangential components, and the flow between adjacent buckets having a free surface.

12. In an impulse turbine means for forming a cylindrical free jet having its axis substantially in a plane perpendicular to the runner axis, and a runner having buckets adapted to receive said jet and to turn all of said jet to one side of said plane and to spread the flow laterally with a free surface and to discharge a portion of it outwardly with respect to the runner axis.

13. In an impulse turbine means for forming a cylindrical free jet having its axis substantially in a plane perpendicular to the runner axis, and a runner having buckets adapted to receive said jet and to turn all of said jet to one side of said plane and to spread the flow laterally with a free surface and to discharge a portion of it outwardly with respect to the runner axis, the discharge portion of the buckets extending to a greater radial distance from the axis than their entrance edges.

14. In an impulse turbine, in combination, means for forming a cylindrical free jet comprising a nozzle with a central adjustable needle and directing said jet in a plane perpendicular to the runner axis and a runner having buckets with the entrance portion of their faces inclined at a forward angle with respect to the radial direction and discharging all of said jet on one side of the runner, the flow between adjacent buckets having a free surface.

15. In an impulse turbine, in combination, means for forming a cylindrical free jet comprising a nozzle with a central adjustable needle and directing said jet in a plane perpendicular to the runner axis in a direction intermediate between radial and

tangential, and a runner receiving said jet and discharging all of said jet on one side of the runner, said nozzle extending nearer to the runner axis than the outermost portions of the runner buckets and the flow between adjacent buckets having a free surface.

16. In an impulse turbine means for forming a cylindrical free jet having its axis substantially in a plane perpendicular to the runner axis and a runner having buckets receiving said jet and discharging all of it on one side of the runner, said jet having a greater radial than tangential component at the point of entrance to said buckets and the flow between adjacent buckets having a free surface.

17. In an impulse turbine means for forming a cylindrical free jet having its axis substantially in a plane perpendicular to the

runner axis, and a runner having buckets receiving said jet and spreading it laterally so that a portion of said jet is directed in the axial direction at discharge and a portion is directed outwardly from the axis, 25 said jet having a greater radial than tangential component at the point of entrance to said buckets and the flow between adjacent buckets having a free surface.

18. In an impulse turbine means for forming a cylindrical free jet having its axis substantially in a plane perpendicular to the runner axis but having a direction more nearly radial than tangential in said plane, and a runner having buckets with the entrance portion of their faces inclined forward of the radial direction and turning all of said jet to one side of said plane, the flow between adjacent buckets having a free surface.

LEWIS FERRY MOODY.
